IMPACT TOOL TORSION BAR

Hanns Hornschuch, Easton, Pa., assignor to Ingersoll-Rand Company, New York, N.Y., a corporation of New Jersey

Filed Apr. 10, 1961, Ser. No. 101,927
9 Claims. (Cl. 192—30.5)

This invention relates to impact wrenches and particularly to such a tool having mechanism to limit the torque which it can deliver.

Tools of this general nature have been designed heretofore but an unfortunate characteristic of such tools is that they are so long that they are awkward to handle. In some designs the torque limiting mechanism is a separable piece which is apt to be still more awkward to handle.

It is an object of this invention to provide a compact tool cheap to manufacture and easy to adjust as to the feature of torque limitation.

Other objects and advantages of the invention will be in part obvious and in part pointed out hereinafter.

The aforesaid objects of the present invention, and other objects which will become apparent as the description proceeds, are achieved by providing an impact tool having a motor, a rotary hammer and a rotary anvil adapted to be struck by the hammer. There is also provided a spring means between the motor and the hammer for accumulating energy of the motor which causes the hammer to expend the accumulated energy on the anvil as an impact at a predetermined resistance to the turning of the anvil, and a torque limiting means. The torque limiting means has a flexible member arranged to accept the turning moment of the anvil and is fitted to receive a wrench socket, or other similar device. The torque limiting device is further provided with a means to stiffen the flexible member releasably to a predetermined degree to limit the torque transmittable by the flexible member including a rigid member for holding an end of the flexible member against rotation in one direction while permitting elastic rotation in the other direction, and an adjuster at the other end of the flexible member mounted on the anvil to vary such stiffening.

A preferred embodiment of the invention is described herein and shown in the accompanying drawing in which

FIGURE 1 is a central longitudinal section through an impact tool constructed in accordance with the practice of the invention,

FIG. 2 is a perspective view of the end of the casing with the cover removed and illustrating the manipulation of the torque limiting adjustment,

FIG. 3 is a transverse section through FIG. 1 at the line 3—3 looking in the direction of the arrows, and

FIG. 4 is a transverse section at the line 4—4 of FIG. 1 looking in the direction of the arrows.

Referring to the drawing the invention is shown as applied to an impact tool of which the impacting mechanism operates on principles very completely disclosed in United States Patent No. 2,160,150, dated May 30, 1939, granted to F. A. Jimerson et al., and being well known in the art will be described very briefly.

The impact tool consists of a motor of the pneumatic type having a cylinder 10 within which is adapted to revolve a rotor 12 carrying vanes of which one is shown at

2

14. A housing 16 encloses the motor and is provided with bearings 18 and 20 for rotor 12. An end 22 of rotor 12 extends beyond bearing 20 and has gear teeth 24 meshing with planet gears 26 which in turn mesh with gear teeth 5 on a stationary internal gear 28 having flange 30 mounted between the front and rear halves of casing 16 which are bolted together by screws 32. The planetary gears 26 are mounted by means of shafts 34 on a spider 36 rotatably mounted on gear 28 by means of anti-friction bearings 38. Spider 36 forms part of a hammer mechanism which includes a hammer 40 provided with jaws 42 extending longitudinally therefrom for engagement with jaws 44 of an anvil member 46 rotatably mounted in housing 16 on anti-friction bearings 48.

Hammer 40 is adapted to rotate anvil 46 either by continuous coupling of jaws 42 or 44 or by delivering impact therebetween when the resistance of anvil 46 to rotation exceeds some predetermined degree. The impacting in this particular instance is produced by a mechanism 20 very completely described in the Jimerson et al. patent above mentioned in which in this instance includes a cam 50 cut inclined or spiral on the interior surface of hammer 40 which cooperates with an oppositely inclined cam face 52 formed on the forwardly extending portion 54 of spider 36. Coil spring 56 encircling spider portion 54 is adapted to push hammer 40 in a forward direction to inter-engage jaws 42 and 44 and for this purpose spring 56 bears against an internal shoulder 58 of hammer 40 and against a ring 60 encircling spider portion 54 and rotatably supported without friction thereon by ball bearings 62 riding in a race 64 formed on spider 36. Thus as hammer 40 is held against rotation by jaws 44, the rotation of spider 36 being continued cams hammer 40 backwardly against the force of spring 56 due to the opposite inclinations of cam grooves 50 and 52 and the balls 62 interposed therebetween. The compression of spring 56 causes an accumulation of energy from the driving motor which increases in amount until jaws 42 are withdrawn from engagement with jaws 44.

Previous to such disengagement the spider 36 has continued to rotate with respect to the hammer 40 and, as the above mentioned patent describes, the energy in spring 56 becomes available to accelerate hammer 40 to catch up with spider 36 as well as to push hammer 40 forward for subsequent reengagement of jaws 42 with jaws 44. The high rotational speed imparted to hammer 40 causes a sharp blow to be struck at jaws 44 and anvil 46. Such impact and the torque delivered to anvil 46 as above described is adapted to be expended through a rod 64 coupled to anvil 46 and provided at its end with suitably squared faces 66 to receive a suitable wrench socket, screwdriver blade and the like (not shown).

Rotor 12, the hammer mechanism and anvil 46 are all 55 hollow and in alignment and together form a central longitudinal passage 68 through which rod 64 extends. The coupling of rod 64 and anvil 46 is accomplished by a suitable means whereby one part may be rotated relative to the other. Such means here includes spirally disposed splines 70 extending generally axially of the 60 interior of anvil 46 meshing with corresponding splines 72 formed on a bushing member 74 fitting on the end of rod 64. In section, rod 64 is known in the trade as "quarter-octagon" being square with the corners chamfered. The hole in bushing 74 is likewise quarter-octagon

to receive rod 64. A rod long and slender bar like rod 64 is ill-adapted to transfer torque from anvil 46 to its end 66 unless or until it is wound up to a suitable torque in amount equalling that to be transmitted. When so wound up it is capable of transmitting lesser torques and up to that point acts as a rigid member.

When the torque to be transmitted comes intermittently as with the hammering mechanism above described means has to be provided to produce the effect of continued winding up of the rod 64 to the required degree. In this instance, such means is provided by a rigid tube 76 supported by anvil 46 and in this instance formed integrally therewith and extending about rod 64 up to the end 66 thereof. The end 78 of tube 76 is provided with a squared aperture 80 slightly larger than rod 64 so that when rod 64 is twisted it will bind in hole 80 but upon turning in the opposite direction considerable play is provided.

To wind up rod 64 means is provided to push against the opposite end of rod 64 and bushing 74 so as to rotate those two parts with respect to anvil 46 by virtue of the inclination of the splines 70 and 72.

To provide such thrust a screw member 82 is provided to screw into the threaded end 84 of anvil 46 and bear against the head of rod 64 which transmits the thrust also to bushing 74 through a keeper ring 36 in rod 64 and transmit thrust onto the head.

Access to the screw 82 is provided by a recess 88 in housing 16 which can be closed by a suitable cover 90. As a convenient means of turning screw 82 a hexagonal hole is provided therein as shown at 92 which will accommodate an Allen-wrench 94.

In order to adjust the tension in rod 64 it is merely necessary to hold the end 66 in a vise or by a wrench and turn screw 82 the required amount. If desired, the screw 62 may be provided with numbers as shown in FIG. 2 and the anvil 46 may have an index as shown by the arrow. Suitable calibration will indicate the degree of turning.

As has been said above blows struck by the hammer mechanism through the jaws 42 to the jaws 44 of anvil 46 will be transmitted through rod 64 as though that rod were rigid up to the extent of the torsion initially given to that rod by turning of screw 82. That torque can be of course applied to the work through the socket wrench or other device attached to end 66. When the resistance to turning of the work exceeds that predetermined amount, rod 64 yields and there is a resultant recoil of hammer 40 which is ineffectual to produce work although it may lengthen the recoil of the hammer and possibly cause an increasedly powerful blow on anvil 46. No benefit is obtained at the work since rod 64 will yield.

Some advantage may be taken of the excessive rebound by way of mechanism to stop the operation of the hammer by closing down the throttle but such mechanism is not part of this invention and is not described here in detail. At 100 is indicated a trigger which may be struck by the end of hammer 40 to shut down the tool in any well known manner. This particular torque limiting arrangement lends itself well to such an application since the recoil of hammer 40 at torques in rod 64 below the predetermined amount have no particular significance and are relatively small, whereas upon reaching the predetermined torque for which the apparatus is set the recoil of hammer 40 becomes relatively violent.

As illustrated the housing 16 may be formed with a suitable handle 102 for manipulation and the throttle plunger 104 is conveniently mounted therein.

Thus, by the above construction are accomplished, among others, the objects hereinbefore referred to.

I claim:

1. For an impact tool having a motor, a rotary hammer, a rotary anvil, said motor, hammer and anvil being coaxial and centrally apertured to form a continuous passage therethrough, means cooperative with said

hammer and said anvil to cause said hammer to impact said anvil rotatively, a torque limiting means comprising a rigid tubular member fixedly attached to said anvil and extending through said passageway, a flexible rod extending the length of said impact tool supported by said anvil and extending through said tube to receive a wrench socket, screwdriver blade and the like, and coupled to said tube adjacent such socket, and means to twist said flexible rod at said anvil to a predetermined torque value with respect to said tube.

2. The device as set forth in claim 1 in which said twisting means includes a splined coupling to vary the angular relation between said rod and said anvil and a screw to maintain such relation.

3. For an impact tool having a motor, a rotary hammer, a rotary anvil adapted to be struck by said hammer, spring means interposed between said motor and said hammer for accumulating energy of the motor as resistance to rotation of the anvil increases and to cause said hammer to expend such accumulated energy on said anvil as an impact at a predetermined resistance to turning of said anvil, a torque limiting means comprising a flexible member extending the length of said impact tool arranged to accept the turning moment of said anvil and fitted to receive a wrench socket, screwdriver blade, and the like, and means to stiffen said member releasably to a predetermined degree to limit the torque transmittable by said member including a rigid member for holding an end of said flexible member against rotation in one direction while permitting limited rotation in the other direction, and an adjuster at the other end and mounted on said anvil to vary such stiffening.

4. For an impact tool having a motor, a rotary hammer, a rotary anvil adapted to be struck by said hammer, said motor, hammer and anvil being in alignment and together forming a central longitudinal passage, spring means interposed between said motor and said hammer for accumulating energy of the motor as resistance to rotation of the anvil increases and to cause said hammer to expend such accumulated energy on said anvil as an impact at a predetermined resistance to turning of said anvil, a torque limiting means comprising a flexible member disposed in said passage and extending the length of said impact tool, through said passage and arranged to accept the turning moment of said anvil and fitted to receive a wrench socket, screwdriver blade and the like, and means to stiffen said member releasably to a predetermined degree to limit the torque transmittable by said member including a rigid member for holding an end of said flexible member against rotation in one direction while permitting limited rotation in the other direction, and an adjuster at the other end and mounted on said anvil to vary such stiffening.

5. For an impact tool having a motor, a rotary hammer, a rotary anvil adapted to be struck by said hammer, said motor and anvil being in alignment and together forming a central longitudinal passage, spring means interposed between said motor and said hammer for accumulating energy of the motor as the resistance to rotation of the anvil increases and to cause said hammer to expend such accumulated energy on said anvil as an impact at a predetermined resistance to turning of said anvil, a torque limiting means comprising a flexible member extending the length of said impact tool arranged to accept the turning moment of said anvil and fitted to receive a wrench socket, screwdriver blade and the like, means to stiffen said member releasably to a predetermined torque to limit the torque transmittable by said member including a rigid member for holding an end of said flexible member against rotation in one direction while permitting limited rotation in the other direction and an adjuster at the other end and mounted on said anvil to vary such stiffening, a housing for said motor, hammer and anvil having an aperture adjacent said motor through which said flexible member extends.

6. The device as set forth in claim 4 in which said rigid member is tubular and extends longitudinally within said passage.

7. The device as set forth in claim 6 in which said hammer is supported at one end on said tubular member. 5

8. The device as set forth in claim 3 in which said flexible member and said rigid member are provided with a spirally splined coupling and said adjuster includes a screw to force said members axially relatively to each other. 10

9. The device as set forth in claim 8 in which said

housing is provided with an opening through which said flexible member projects and a second opening giving access to said screw.
